UNITED STATES PATENT OFFICE.

ROBERT JAMIESON, OF UTICA, NEW YORK, ASSIGNOR TO DRAPER CORPORATION, OF HOPEDALE, MASSACHUSETTS, A CORPORATION OF MAINE.

WARP STOP MECHANISM FOR LOOMS.

Application filed January 18, 1926. Serial No. 81,930.

This invention relates to mechanical warp stop mechanisms for looms and is more particularly directed to the location of the warp fault which may result either from a broken 5 or too slack warp thread.

It is now the common practice to provide looms with warp stop mechanisms, one form of which comprises drop wires normally supported by the warp threads during weaving, 10 and a drop wire detector having a detecting movement, adapted to be arrested by a drop wire on the occurrence of a warp fault, and thereupon effect loom stoppage.

Much difficulty is experienced in locating 15 the particular warp thread which has caused the loom to stop, and efforts have been made to provide means for this purpose, some of which give a twisting movement to a drop wire when it is released by a broken or too slack warp thread, and in others of which 20 the drop wire detector itself is utilized to move the fallen drop wire into a warp fault indicating position.

One of the objects of the present invention 25 is to provide a warp stop mechanism with warp fault indicating means, by which the downward movement of a released drop wire will at once indicate to the loom attendant where the warp fault has occurred, without 30 at the same time subjecting the drop wire itself to any bending, twisting or other movement calculated to injure the drop wire.

In accordance with the present invention, 35 the warp fault indicating means comprises a deflector located at the lower portion of the warp support and having a downwardly and outwardly inclined surface which is normally below the lower ends of the drop wires during weaving, but upon which the 40 lower end of a drop wire will move and by which it will be deflected into its indicating position upon the occurrence of a warp fault.

A further feature of the invention consists in providing the warp fault locating 45 deflector with division walls between which the lower ends of the drop wires may move as they pass along the downwardly inclined deflecting surface into the path of the drop 50 wire detector.

During weaving, the warp threads frequently have a lateral movement, that is, a movement transversely of the loom, and when this becomes excessive, the drop wires 55 are liable to interfere with each other when

one of them is released by a broken or too slack warp thread. Another feature of the invention, therefore, consists in providing the warp fault locating deflector with a vertically extending surface which projects 60 above the lower ends of the drop wires during weaving, the division walls of the upwardly extending surface acting at such times to maintain the drop wires from lateral displacement. 65

The invention and novel features and new combination of parts will best be made clear from the following description and the accompanying drawings of one good form thereof. 70

In the drawings:

Fig. 1 is a perspective view partly broken away of a mechanical warp stop mechanism provided with the present invention, the drop wires being shown in their supported 75 or raised position; and

Fig. 2 is a cross-section of the warp stop mechanism showing one of the drop wires as having been released by its warp thread and deflected by the downwardly inclined 80 surface of the deflector.

The means for effecting loom stoppage on the occurrence of a warp fault is not herein shown because the details thereof form no part of the present invention and are now 85 well understood.

Rising from the loom frame are the vertical supports 1, one at each side of the loom, upon which are adjustably secured the foot portions 2 of the side brackets or supports 3. 90 Extending downwardly from each of the side brackets 3 is an arm 4 in which is mounted the detector vibrating shaft 5, and secured to the shaft 5 are the detector arms 6, to the upper end portions of which is 95 secured the detector or feeler 7, which may be secured to the arms by appropriate means such as the screws 8.

The detector shaft 5 has extending therefrom the arm 9 connected by a rod 10 to 100 suitable means on the lower or cam shaft of the loom, for imparting to the detector its vibrating or detecting movement, but since such train of mechanism is now well known and understood by those familiar with the art, it is not herein shown and described as the details thereof form no part of the present invention, the essentials being, as usual, that the detector be given its vibrating or detecting movements and upon arrest 105 110

thereof by a fallen drop wire that the loom shall be stopped to enable the loom attendant to piece up the broken or too slack warp thread.

5 Extending transversely of the loom between the side brackets or supports 3 are the warp supports 11, herein shown as comprising rectangular members upon the top edge portion of which the warp threads a 10 rest during weaving.

15 The drop wires 12 are herein shown as formed of light sheet metal and provided each with an opening 13 through which a warp thread passes and by which the drop wires are supported during weaving. Each 20 of the drop wires extends a substantial distance above the plane of the warp threads and is provided with an opening 14 through which extends the drop wire guide 15 which 25 may be conveniently supported at each end by the side brackets or support 3. The construction so far described may be as usual or of any preferred form, with the exception that the openings 14 in the drop wires are enlarged or made wider than usual, so 30 that when a drop wire is released by its warp thread it may be deflected out of the line of the series of drop wires to locate the warp fault, as will hereinafter be more fully described.

35 Mounted adjacent the lower ends of the warp supports 11, two of which are shown in the present instance, are the warp fault locating deflectors 16, which are of novel construction. The deflectors 16 are herein shown as secured to the inner portions of the warp supports adjacent their lower ends, and one convenient means of securing the 40 deflectors in the desired position may be constituted by the screws 17 passed through the lower portions of the warp supports and into the body portion of the deflectors.

45 Each deflector 16 is provided with a downwardly deflecting surface 18 which is normally below the lower ends of the drop wires when the latter are in their normal supported position during weaving, the construction being such, in this respect, that should a drop wire be released by its associated warp thread, it will drop from its raised to its lowered position, as indicated in Fig. 2, and the lower rounded edge portion 19 of the drop wire will ride along the 50 downwardly inclined surface 18 of the deflector into the path of the vibrating detector, to thereby cause loom stoppage.

55 Each of the deflectors 16 is provided with division walls 20 between which the lower end portions of the drop wires may move and by which they may be guided when they are deflected into the path of the detector 7. In the present instance of the invention, each deflector 16 has an upwardly extending portion 21 provided with a substantially 60 vertical surface 22 located adjacent the

lower ends of the drop wires when the latter are supported by the warp threads during weaving, and the vertical surface 22 of each deflector merges, as at 23, into the downwardly inclined deflecting surface 18.

65 The division walls 20 of each deflector are shown as carried upwardly along the vertical surface 22, with the result that the lower end portion of the drop wires when they are normally supported by the warp 70 threads during weaving may rest between the division walls adjacent the vertical surface 22 of the deflector, and thereby prevent lateral or sidewise movement of the drop wires during weaving.

75 In the present instance of the invention, each deflector 16, constructed substantially as hereinbefore described, is shown as having the division wall formed by cutting into the material of the deflector, but it is evident that such division walls may be otherwise provided, the essentials in this regard being that when a drop wire is released by its warp thread, owing to breakage or too slack condition of such warp thread, the lower rounded end portion of the drop wire 80 may ride along the downwardly inclined deflecting surface 18 and be guided in such movement by the division walls, and where the division walls 20 extend upwardly adjacent the vertical surface 22, they may act, by engagement with the lower ends of the drop wires when normally supported by the warp threads, to prevent lateral movement 85 of the drop wires.

90 During weaving, the drop wires 12 are normally supported by the warp threads which rest upon the top surfaces of the warp supports 11, and where the deflector is carried upwardly, as indicated, and the division walls themselves are likewise carried upwardly, opposite the lower ends of the drop wires when in normal position, such division walls maintain the drop wires 95 from lateral displacement.

100 Should a warp thread break or become too slack for weaving purposes, the associated drop wire will move downwardly, the lower end at such times engaging the inclined deflecting surface 18 of the deflector below it, and the released drop wire will be deflected into the position indicated in Fig. 2, the lower end portion at such times passing into the path of movement of the drop wire detector, and the upper portion of the drop wire, as indicated at Fig. 2, will be displaced or deflected from the line of drop wires, to indicate the location of the warp fault. In order that such deflection may take place, the openings 14 in the drop wires are made sufficiently wide not only to accommodate the drop wire guides 15, but to permit the drop wires themselves to be deflected by the deflector when released by the associated warp thread.

As indicated at the left of Fig. 2, the preferred construction contemplates that the lower end portion of each drop wire shall rest against the vertical surface 22 at 5 the upper portion of the associated deflector and that the drop wire guide 15 may at such times rest against the side surface 24 forming one wall of the opening 14 in each drop wire, the result being that when a drop 10 wire is released, it will move downwardly, its lower rounded end 19 traveling between the division walls, and engage the deflecting surface 18, while the upper portion of the drop wire will be displaced from the 15 line of drop wires.

In the present instance of the invention, only two banks of drop wires are shown, but it is evident that any number of banks 20 of drop wires may be employed in connection with the present invention, which is constituted more particularly by the warp fault locating deflector which may be readily applied to any of the existing warp stop mechanisms now in use. The invention is 25 simple, effective and easily applied, and serves to indicate the warp fault by the fact that the upper portion of the released drop wire when in its deflected position, as indicated in Fig. 2, will be a substantial distance 30 above the plane of the warp threads.

What is claimed is:

1. In a mechanical warp stop mechanism for looms, the combination of a series of drop wires normally supported by the warp 35 threads during weaving, warp supports one at each side of the series of drop wires on which the warp threads rest, a drop wire deflector projecting from the inner face of the warp supports and each having an inclined surface diverging downwardly from the inner face of the warp supports for deflecting a released drop wire, and a vibrating detector adapted to engage and be stopped by a deflected drop wire.

45 2. In a mechanical warp stop mechanism for looms, the combination of a series of drop wires normally supported by the warp threads during weaving, a warp support on which the warp threads rest during weaving, 50 a detector having a detecting movement towards and from the vertical plane of the normally supported drop wires, a fixed drop wire deflector having a downwardly inclined deflecting surface arranged in the vertical path of downward movement of a drop wire when it fails to be supported by a warp thread during weaving that the lower end 55 of the released drop wire will ride over the inclined deflecting surface of the deflector as it moves downwardly from its normally supported position and cause the upper end of the released drop wire to be tilted to one side of the plane of the normally supported drop wires prior to engagement by the detector.

3. In a mechanical warp stop mechanism for looms, the combination of a series of drop wires which project a substantial distance above the plane of the warp threads in both their supported and released positions, 70 warp supports one at each side of the series of drop wires on which the warp threads rest during weaving, a warp fault locating deflector at the lower inner portion of the warp supports each having a downwardly 75 diverging inclined deflecting surface acting to tilt a released drop wire to locate the warp fault, and a drop wire detector having a detecting movement below the normally supported drop wires during weaving and towards the path of which the lower end of the drop wire is deflected on the occurrence of a warp fault.

4. In a mechanical warp stop mechanism for looms, the combination of a series of drop wires which project a substantial distance above the plane of the warp threads in both their supported and released positions, 80 warp supports on which the warp threads rest during weaving, a warp fault locating deflector at the lower inner portion of the warp support having an inclined deflecting surface diverging downwardly from the inner surface of the warp supports 85 and acting to tilt a released drop wire to locate the warp fault and division walls between which the lower end of a drop wire has guided vertical movement during weaving, and a drop wire detector having a detecting movement below the normally supported drop wires during weaving and into the path of which the lower end of the drop wire is deflected on the occurrence of a warp fault.

5. In a mechanical warp stop mechanism 105 for looms, the combination of a series of drop wires which project a substantial distance above the plane of the warp threads in both their supported and released positions, warp supports on which the warp 110 threads rest during weaving, a warp fault locating deflector secured at the lower inner portion of each of the warp supports having a vertical portion merging into a downwardly diverging inclined deflecting surface 115 acting to tilt a released drop wire to locate the warp fault, and a drop wire detector having a detecting movement below the normally supported drop wires during weaving and into the path of which the lower end of the drop wire is deflected on the occurrence of a warp fault.

6. In a mechanical warp stop mechanism 125 for looms, the combination of a series of drop wires which project a substantial distance above the plane of the warp threads in both their supported and released positions, warp supports on which the warp threads rest during weaving, a warp fault locating deflector secured to the lower inner portion of each of 130

the warp supports having a vertical surface extending above the lower ends of the drop wire when normally supported by the warp threads and a downwardly inclined deflecting surface acting to tilt a released drop wire to locate the warp fault, and a drop wire detector having a detecting movement below

the normally supported drop wires during weaving and into the path of which the lower end of the drop wire is deflected on the occurrence of a warp fault.

In testimony whereof, I have signed my name to this specification.

ROBERT JAMIESON.
